UNITED STATES PATENT OFFICE.

PAUL D. SPRENGER AND CHARLES W. MCPHERRON, OF SEATTLE, WASHINGTON.

VALVE.

Application filed February 7, 1924. Serial No. 691,228.

To all whom it may concern:

Be it known that we, PAUL D. SPRENGER and CHARLES W. MCPHERRON, citizens of the United States, residing at Seattle, in the county of King, State of Washington, have invented certain new and useful Improvements in Valves, of which the following is a specification.

Our invention relates generally to improvements in valves, more particularly to improvements in valves of that type which is adapted to be applied to a tank for a liquid fuel to control the flow of liquid fuel from the tank, and it consists in the combinations, constructions, and arrangements herein described and claimed.

An object of the invention is to provide a valve mechanism of simplified construction which is adapted to permit flow of liquid fuel from a tank with which the valve mechanism is associated until only a given quantity of liquid fuel remains in the tank and to then stop the further flow of fuel from the tank until the valve has been operated, whereby the operator is apprised that the supply of fuel is nearly exhausted at the time when a quantity of fuel sufficient to supply fuel to the engine of a motor driven vehicle until such vehicle can be driven to a filling station remains.

A further object of the invention is to provide a valve mechanism of the character described which is not likely to get out of order easily, takes up but little space when applied to a fuel feed tank of ordinary construction, and which is thoroughly practical commercially.

Other objects and advantages will be apparent from the following description, considered in conjunction with the accompanying drawings, in which:

Figure 1 is a vertical section through a portion of a liquid fuel tank of an ordinary construction, showing our improved valve mechanism applied thereto, the valve mechanism being shown in side elevation.

Figure 2 is a slightly enlarged fragmentary vertical sectional view showing the tubular valve casing of the device with the rotary valve therein in open position.

Figure 3 is a view similar to Figure 2, showing the valve in closed position.

Figure 4 is a still further enlarged fragmentary vertical sectional view showing the portion of the mechanism which is disposed at the upper end or top of the tank,

Figure 5 is a relatively enlarged perspective view showing the valve member of the device.

Figure 6 is a vertical sectional view through the valve casing and taken substantially at right angles to the view in either Figure 2 or Figure 3, and

Figure 7 is an enlarged plan view of a hand-wheel which is comprised in the device.

Referring now to the drawings, we show in Figure 1 a portion of a liquid fuel tank 1 which may be of any suitable known or preferred construction, such as ordinarily adapted for use on a motor car. The tank 1 has an outlet opening 2 in the bottom thereof and a flange 3 may be secured to the bottom member of the tank in such position that the central opening 4 of the flange is in register with the opening through the bottom of the tank. The central opening 4 is screw-threaded for engagement with the externally threaded tubular intake member 5 of a trap 6 or like receptacle for receiving liquid from the tank. The liquid received in the trap 6 may pass therefrom through a delivery tube 7 for use at any convenient place. The trap 6 may have a sediment chamber in the lower part thereof provided with a drain opening controlled by a pet cock 8, as is usual. The parts described so far are ordinary in construction and form no part of our invention except in so far as they co-operate with the parts which will now be described.

In carrying out our invention we provide a tubular valve casing 9 which has an end portion thereof provided with external screw threads 10 for engaging with the internally screw-threaded intake member 5 of the receptacle 6. The tubular valve casing 9 has a lateral port 11 formed through the walls thereof at the inner end of the screw-threaded portion 10.

A tubular rotary valve 13 is adapted to interfit the valve casing 9 in such manner as to be readily rotatable in the latter but to have a substantially fluid-tight fit with the valve casing. The valve 13 has the walls thereof cut-away from one end thereof for part of the length of the valve as indicated at 14, the opening thus provided at 14 extending less than one-half the circumference of the valve.

A valve stem 15 has an end portion thereof received within the adjacent end portion of the valve 13 and is rigidly secured to the latter through the agency of a pin 16

which extends diametrically through the lapped portions of the valve and valve stem. The valve stem 15 is considerably smaller in diameter than the valve 13 so that a liquid may flow from the valve casing 9 into the valve 13 at the upper end of the latter and between the valve stem and the inner wall of the valve when the parts of the device which have been described are disposed within the tank 1 in the position illustrated in Figure 1. It will be observed by referring to Figure 1 that the valve casing 9 will be supported to extend vertically within the tank 1 when the threaded lower end portion 10 of the valve casing is engaged with the intake member 5 of the receptacle 6. The valve stem 15 extends from the valve casing 9 vertically through the tank 1 and through an opening 17 in the top of the tank. The opening 17 is in vertical alignment with the opening 2 and the valve stem is supported and guided by an elongated guiding and supporting member 18 which may be secured at its lower end by solder or other suitable known means to the tubular valve casing and is provided at its upper end with a laterally extending portion 19 having an opening 20 through which the valve stem 15 extends. The laterally extending portion 19 of the guide and supporting member also serves to clamp a packing washer 21 which encircles the valve stem 15 against the top of the tank 1, the washer 21 being made of felt or like compressible material and serving to prevent leakage between the wall of the opening 17 and the portion of the valve stem which extends through such opening. The valve stem 15 may be provided above the laterally extending portion 19 with any suitable known means for engaging with the laterally extending portion 19 to prevent downward movement of the valve stem 15 in the direction of its length.

The end portion of the valve stem which protrudes from the opening 17 and extends above the top of the tank has a hand-wheel 22 secured thereto by a set screw 23 which is inserted in the counterbore 24 at the outer end of a radial opening which opens into the central opening of the hand-wheel and which is threaded for engagement with the threaded shank of the screw.

The hand-wheel 22 preferably has a plain upper face having arrows or like indicia, as indicated at 25 and 26, respectively, the respective arrows being associated with the words "Closed" and "Open" and indicating the directions in which the hand-wheel 60 should be turned to move the valve 13 to or from position to close the lateral port 11 of the valve casing. The valve stem 15 is provided adjacent to its upper end with a laterally extending arm 27 which is adapted 65 to contact with one edge portion of the

guide 18 when the stem and valve have been rotated as a unit until the valve is in closed position and to contact with another portion of the guide 18 when the valve stem and valve have been rotated as a unit until the valve is in open position.

From the foregoing description of the various parts of the device, the operation thereof may be readily understood. The device is assembled as follows: The trap or receptacle 6 is removed from the tank and the valve casing 9 is screwed into the intake member of the receptacle. The hand-wheel 22 is removed from the upper end portion of the stem 15 and the parts of the device which are supported on the valve casing are inserted in the tank 1 through the opening 2. It will be manifest that when the receptacle 6 is turned or rotated until the threaded intake member 5 thereof is screwed into the opening 2 the parts of the device which are carried by the trap will be moved vertically until the upper end portion of the valve stem extends through the opening 17 in the top of the tank and the packing washer 21 will be compressed between the laterally extending portion 19 of the guide and the top of the tank. The hand-wheel 22 then is secured on the extending upper end portion of the valve stem.

When the tank has been filled with liquid fuel in the usual manner, the liquid will flow by gravity through the valve casing 9 and the tubular valve 13 into the receptacle 6 so long as the level of liquid within the tank does not fall below the level of the upper end of the valve casing 9, irrespectively of the position of the valve 13 in the valve casing. However, when the valve 13 has been rotated to position to close the lateral port 11, flow of liquid through the valve casing and from the tank will be interrupted whenever the level of liquid within the tank falls below that of the upper end of the valve casing. The lateral port 11 is so positioned along the valve casing that the lower side thereof is at approximately the same level as the bottom of the tank so that liquid will be permitted to flow through the lateral port 11 into the valve casing and therefrom into a receptacle 6 when the valve 13 has been rotated to position to uncover the lateral port 11. Therefore, the tank 1 may be completely emptied by gravity when the valve is in open position.

Obviously, our invention is susceptible of embodiment in forms other than that illustrated in the accompanying drawings and we, therefore, consider as our own all modifications and adaptations thereof which fairly fall within the scope of the appended claims.

We claim:—

1. The combination with a liquid fuel tank having an opening through the upper

part thereof and also having an opening in the lower part thereof in vertical alignment with said first opening, of a tubular valve casing supported at its lower end in 5 said second-named opening and upstanding within the tank for part of the height of the latter, said tubular valve casing having a lateral port adjacent to the lower end thereof, a rotary valve in said valve casing for controlling said port, a valve stem for operating said valve, said valve stem extending vertically within the tank through the opening in the upper part thereof, a valve 10 stem guiding and supporting member supported upon said valve casing and extending vertically within said tank, a packing washer surrounding said valve stem and compressed between said valve stem guiding and retaining member and the upper wall 15 of said tank, and a hand-wheel secured to the extending upper end portion of said stem, said valve casing, valve stem, packing washer and stem guiding and supporting member being insertable in the tank through 20 the opening in the lower part of the tank.

25 2. The combination with a liquid fuel tank having an opening through the upper part thereof and also having an opening in

the lower part thereof in vertical alignment with said first opening, of a tubular valve 30 casing supported at its lower end in said second-named opening and upstanding within the tank for part of the height of the latter, said tubular valve casing having a lateral port adjacent to the lower end thereof, a rotary valve in said valve casing for controlling said port, a valve stem for operating said valve, said valve stem extending vertically within the tank through the opening in the upper part thereof, a valve 35 stem guiding and supporting member supported upon said valve casing and extending vertically within said tank, a laterally extending arm carried by said valve stem for engaging with said guiding and supporting member when the valve stem has been rotated to position to cause closing of said valve, and a hand-wheel secured to the extending upper end portion of said valve stem, said hand-wheel having indicia thereon indicating the direction of rotation of 40 said hand-wheel to effect closing of the valve.
